SKIN FASTENER

Peter F. Rossmann, Snyder, N. Y., assignor to
Irving Rossi, West Orange, N. J.

Original application December 19, 1941, Serial
No. 423,565. Divided and this application Jan-
uary 6, 1942, Serial No. 425,716

12 Claims. (CL 85—5)

This application is a division of my co-pending application Serial No. 423,565, filed December 19, 1941, entitled "Skin fastener."

The present invention relates to a clamping device or skin fastener and a method of making the same and which serves for temporarily assembling or clamping together perforated sheet material, in particular metal sheets or plates preparatory to and to facilitate a riveting operation or any other work to be carried out on said material.

In my copending application, Serial No. 384,461, filed March 21, 1941, entitled Clamping device, I have described a device of this character comprising essentially a body member or support provided with an opening preferably equal to the perforations in the sheets or other material to be clamped, a clamping element arranged in movable relation to said support and having a pair of resilient legs or prongs provided with shoulders and biased into engagement with each other, and a spreader arranged in relatively fixed relation to said support and projecting through said opening. Normally the spreader is interposed between said prongs to hold the same in spaced apart position against their natural bias with the combined cross-sectional area of said prongs and interposed spreader being substantially equal to and filling said opening. Furthermore, I provide suitable spring means interposed between said spreader and clamping element to permit of movement of said clamping element between two extreme positions, one of said positions resulting in the ends of said prongs and said shoulders passing beyond said spreader and being operated into engagement with each other in such a manner as to enable the insertion of said prongs through the aligned perforations of a pair of sheets or any other piece to be clamped, and the other of said positions resulting in clamping engagement and firm locking of said sheets or piece between said support and shoulders held in spaced apart position by said spreader.

An object of the present invention is the provision of various features of improvement embodied in a device of the above general character both in order to simplify the construction and to improve the operation thereof.

A specific object is to provide a simplified skin fastener, the component parts of which are reduced to a minimum and which can be quickly and easily assembled and disassembled during manufacture and for the exchange of broken or defective parts.

Another object is to permit the use of heavy

clamping forces especially as required for riveting operations substantially without damage to the metal sheets.

A further object is the provision of a simplified clamping device constructed in such a manner as to enable quick and instant insertion through the perforations in the sheets to be assembled or clamped even in the hands of an unskilled or untrained operator.

Another object is to provide a fastener which while small in size will permit of applying considerable clamping pressure between a pair of perforated sheets capable of withstanding the forces exerted thereon during a riveting or other operation.

Still another object is the provision of a clamping device of the above type simultaneously adapted for removing the burr on the edge of the perforations of the sheets being clamped, or in other words, to provide a combined clamp and reamer for use on perforated material.

The above and further objects and advantages of my invention will become more apparent from the following detailed description taken with reference to the accompanying drawing forming part of this specification and wherein:

Figure 1 is a vertical cross-sectional view of a skin fastener constructed in accordance with the principles of the invention; Figure 2 is a cross-section taken on line 2—2 of Figure 1; Figure 3 is a partial view of the improved clamping element embodied in Figure 1; Figure 4 is a perspective partial view showing the spreader embodied in Figure 1; Figure 5 is a vertical view showing a fastener constructed and used on skin sheets in about twice natural size in the inserting position during the operating cycle; and Figure 6 is a perspective view showing the novel locking element for holding the parts of the clamp in the assembled position.

Like reference characters identify like parts in the different views of the drawing.

In the drawing, the numeral 10 indicates the body member or support of my improved fastener which, in the example shown, has the shape of a cup 10 provided with a flange 11 at its open end and having a bottom 12 curved or outwardly vaulted as shown in 13. Bottom 12 is provided with a central opening or perforation 14 which is preferably equal in diameter to the aligned holes or perforations in a pair of super-posed sheets A and B, or any other piece to be clamped or assembled.

The clamping element 15 which is shown separately in Figure 3 is constituted, according to the

improved method and construction by a unitary wire member of semi-circular or segmental cross-section as shown in Figure 2, bent into a U-shape with the flat surfaces facing each other to form a pair of resilient legs or prongs. The latter are shaped as shown in Figure 3 to comprise a first pair of substantially parallel sections 18 and 18' adjacent to their bent portion, followed by intermediate sections 17 and 17', being at first bent inwardly at a small angle (15°) to the central or symmetry line and then outwardly at a slight angle (about 3°), the lowermost or outer sections 18 and 18' provided with shoulders or protuberances 20 and 20' being in turn substantially parallel for a distance at least equal to the cross-piece 22 plus the thickness of the member 10 at its perforation 14 plus the thickness of the plates A and B. These parallel portions 18 and 18' are urged or biased into engagement with each other in the normal position as shown in Figure 3.

The parallel outer prong sections 18 and 18' are passed through the opening 14 in the bottom 12 and are held in spaced apart position both in the ineffective or non-use and in the operative position by a substantially T-shaped member comprising a spreader 21 (see Figure 4) and a cross-piece 22 interposed between said prongs in sliding engagement with the flat inner faces thereof as shown in Figure 1. The under-surface 23 of the spreader portion or cross-piece 22 is suitably curved to substantially conform to the inside of the bottom 12 with which it cooperates in maintaining the spreader 21 in a predetermined position relative to the cup or body member 10.

The upper end of the clamping member 15 projects beyond the cup 10 and has secured thereto a head or cap 25 by the aid of a cross-pin 26 passed through diametrical perforations in the cap and embracing the bent outer portion of the prongs. Pin 26 is held in position by a slit resilient ring-shaped locking element 27 placed in a circumferential groove of the cap 25 to enable an easy assembly and disassembly of the device during manufacture and for the quick exchange of broken or defective parts during use, as will be described in greater detail hereafter. The locking ring 27 is preferably of resilient steel wire and slit as shown in Figure 6 with the ends biased away from each other to allow of sufficient separation for insertion in the grooves of cap 25 and locking therein in a manner well understood.

A coil spring 30 encircling the prongs of element 15 has its upper end engaging the upper surface of the spreader portion 22, the upper end of the spring resting within the recess formed by an angular flange 31 in the undersurface of and engaging the cap 25. Spring 30 is designed to provide sufficient clamping force to firmly lock the shoulders 20 and 20' against the undersurface of sheet B in the operative position of the fastener as shown in Figure 1, or against the undersurface of the bottom 12 in the ordinary or non-use condition of the device. To this end, for a clamping device of the size here illustrated for clamping 16" sheets, the spring employed is such that it requires thirty-five pounds to separate the sheets.

The vaulted or curved construction 13 of the bottom 12 of the cap or body member 10 enables the employment of a comparatively very heavy spring to secure an adequate clamping or firm locking of the sheets A and B by the fastener without the danger of damage to same as by

forming impressions in the sheets or other piece being clamped or assembled. Although shown curved substantially throughout its area, it is to be understood that only the outer edges of the bottom 12 need be curved for the purpose mentioned, thereby obtaining at the same time a desired area for the distribution of the force exerted by the spring 30 and consequently a desired predetermined clamping pressure between sheets A and B.

The clamping element 15 may be produced from a piece of spring steel wire of proper length cut from a suitable supply. According to one practical method, the wire is at first converted from its normal round shape into a flattened and bent shape by means of a suitable pressing operation preferably in two or more steps. Thus, for example, the round straight wire is flattened in a first operation to assume a semi-circular or segmental cross-section and the shoulders 20 and 20' are formed in the same or a subsequent pressing operation by using a suitable die. Then the wire still in a straight position is bent in another die to provide the intermediate sections 17 and 17', whereupon the final U-shape is produced in a subsequent operation with the sections 18 and 18' and shoulders 20 and 20' engaging each other in the manner shown in Figure 3. In this shape the element is then suitably tempered to provide the necessary springiness or resiliency.

An advantage of a clamp or skin fastener described hereinbefore is the fact that none of the component parts thereof are connected permanently, thus enabling an easy and quick assembly during manufacture and disassembly to exchange damaged or defective components. The assembly of the clamp is as follows: To begin with, the spreader 21—22 is placed between the lower parts of the prong sections 17 and 17' of the element 15, the spreader 21 readily fitting between the prongs and with the cross-piece 22 projecting equally from the opposite sides from the prongs. This sub-assembly is then inserted into the cup 10 held in a suitable support or mounting jig, the shoulders 20 and 20' readily passing through the opening 14, until the cross piece 22 engages the inner surface of the bottom 12. The spring 30 is then placed around the prongs. In this uncom-pressed position the spring will extend beyond the upper ends of the prongs. The spring is then compressed by the aid of a suitable tool until the upper end of element 15 sufficiently projects beyond the upper end of the spring, whereupon cap 25 is placed over the prongs and locked in position by passing cross-pin 26 through the holes in the cap and between the prongs, whereby upon subsequent release of the spring the prongs will be drawn in an upward direction. Consequently, sections 18 and 18' will slide over the faces of the spreader 21 thus being spread apart. This upward movement is continued until the shoulders 20 and 20' engage the undersurface of the bottom 12 of cup 10. The locking ring 27 is applied to the cap before or after release of the spring 30. The disassembly of the clamp may be effected in a similar manner by first removing locking ring 27 and then pin 26, thus permitting the removal of spring 30. Element 15 is then pushed in a downward direction until sections 18 and 18' have passed beyond the spreader 21 and are operated into engagement so as to allow withdrawal of

the prongs in a manner understood from the foregoing.

As pointed out hereinafter, the curved or arched shape of the bottom 12 prevents scratching and scarring of the upper skin surface A and in addition has the further effect of concentrating sufficient pressure around the circumference of the perforation in the sheet. When the clamp is used for temporarily holding sheets to be riveted or subjected to any other operation involving substantial forces exerted on the sheets, a sufficient clamping pressure is required to be applied by the spring 30 to prevent the sheets from separating when the rivets are applied to adjacent perforations or during any other work performed on the sheets. This might lead to an unnecessarily heavy spring and a large clamp requiring a strong tool such as a plier for insertion into and removal from the perforations in the sheets. By the improvement proposed according to the present invention, due to the concentration of the pressure upon a small area around the perforation, both the size of the spring and the entire clamp as well as of the operating tool are reduced to a minimum and the operation itself greatly simplified and expedited. Thus, it was found by practical experiments that when the fastener is used to hold a combination of sheet thickness of $\frac{1}{8}$ ", it requires about $16\frac{1}{2}$ pounds to separate the sheets when using a fastener of about one-half the size of that shown in Figure 5. This clamp provides a substantial margin of safety for the performance of riveting operations and it is seen that by employing the improved construction the clamp may be readily adapted to other operating conditions, while maintaining its size and that of the operating tool at a minimum.

The round or curved shape of the bottom 12 has the further advantage of assisting in the alignment of the clamp in the holes in its final position, thereby further simplifying and facilitating the insertion and operation thereof.

While I have shown the support or body member 10 in the form of a cup it will be understood that the same may take any other suitable shape such as a U-shaped metal strip or angle piece or the like sufficient to form a housing support for the device, such modifications and variations of the parts of the device being readily obvious to those skilled in the art.

In use, the cap 25 is pressed against the cup 10 by compressing spring 30 with the aid of a suitable tool such as a toggle device or a plier engaging the outer surface of the cap on the one hand and the undersurface of the flange 11 on the other hand if heavy spring pressures are required such as in clamping sheets for performing a riveting or similar operation. In this (inserting) position the prong sections 18 and 18' are passed beyond the spreader 21 and operated towards each other by their own spring action. The maximum diameter of the prongs and shoulders 20 and 20' when biased towards each other permits of ready insertion through the perforations in the sheets A and B as illustrated in Figure 5 showing the position at the start of the insertion cycle. The shoulders 20 and 20' are designed in such a manner as to provide when in engagement with each other a ready slip fit in the perforations, and, due to the parallel shape of the lower prong sections 18 and 18' it is clearly seen that the insertion is greatly simplified by providing a ready guidance for the prongs through the perforations during the in-

serting operation. Moreover, the parallel arrangement of the lower prong sections 18 and 18' not only insures a ready guidance of the clamp during the insertion into the holes of the sheets to be clamped, thereby substantially dispensing with the necessity of employing a trained or skilled operator, but it furthermore prevents any lateral movement or play of the prongs during the insertion cycle which is not the case in prior constructions wherein the ends of the prongs form an angle and wherein substantially the shoulders only are biased into engagement with each other during the inserting operation. In this position the spreader 21 which substantially conforms to the inner faces of the prong sections 17 and 17' will be readily positioned between the latter, resulting in the prong sections 18 and 18' remaining in parallel position and properly aligned and preventing lateral movement or canting as pointed out above.

At the end of the insertion cycle, that is when the curved bottom 12 engages the upper surface of the sheet A as shown in Figure 1, the spreader 21 will be so positioned with respect to the sheets A and B as to cause the prong sections 18 and 18' and the shoulders 20 and 20' to become spread apart by moving in an upward direction towards the sheets A and B of body member 10 upon release of the spring 30 so as to result in a firm locking or clamping of the sheets between the shoulders 20 and 20' and the bottom 12 in the manner understood from the foregoing and shown in Figure 1.

In order to remove the fastener from the sheets or any other piece upon completion of a riveting or other operation, the spring 30 is again compressed by pressing the cap 20 by the aid of a plier or the like against the cup 10 in the same manner as described above, thereby again operating the prong sections 18 and 18' into engagement with each other and enabling a withdrawal of the prongs from the perforations. After the clamp has been withdrawn the spring pressure is released thus returning it to its normal or non-use position as is readily understood.

It will be evident from the foregoing that the invention is not limited to the specific details of construction and arrangement of parts shown and disclosed herein for illustration but that the underlying novel principles are susceptible of variations and modifications coming within the broader scope of the invention as defined in appended claims. The specification and drawing are accordingly to be used in an illustrative rather than a limiting sense.

I claim:

1. In a device for clamping perforated sheets in superposed relation, a body having an opening, a substantially U-shaped resilient clamping prong of substantially uniform cross-section throughout slidable through said opening and having its outer leg portions provided with shoulders and biased toward each other normally under their own spring tension, a spreader resting against said body and positioned between said legs for maintaining said leg portions in normally spaced relation and forming therewith a cross-sectional area of a diameter equal to the diameter of the perforations of the sheets to be clamped, said outer leg portions being offset towards each other whereby to form when in engagement due to the resiliency of said prong a combined uniform cross-section for a distance at least equal to the total thickness of the sheets to be clamped, said spreader and said body taken

in the longitudinal direction of said prong, spring means arranged to have one end engaging the inner end of said prong and having its opposite end bearing upon said spreader for maintaining said prong in a predetermined normal position with respect to said body and for maintaining said spreader against longitudinal movement with respect to said body in the direction of said prong, said legs when moved beyond said spreader upon movement of said prong relative to said body against the action of said spring means being operated towards each other to permit ready insertion of said legs and shoulders into the perforations of the sheets to be clamped, and said legs on being released moving under the action of said spring means to their normal position with respect to said body and spreader at which said legs are in spaced parallel position, whereby to clamp said sheets between said shoulders and said body.

2. In a device for clamping perforated sheets in superposed relation, a body having an opening, a substantially U-shaped clamping prong slidable within said opening and formed from a single elongated metal member of equal segmental cross-section throughout with the legs of the U having their flat surfaces in face-to-face relation, the outer leg portions of said prong being provided with shoulders and biased towards each other normally under their own spring tension, a spreader resting against said body and positioned between said legs for maintaining said leg portions in normally spaced relation and forming therewith a cross-sectional area of a diameter equal to the diameter of the perforations of the sheets to be clamped, said outer leg portions being off-set towards each other to form when in engagement due to the resiliency of said prong a combined uniform cross-section for a distance at least equal to the total thickness of the sheets to be clamped, said spreader and said body taken in the longitudinal direction of said prong, spring means arranged to have one end engaging the inner end of said prong and having its opposite end bearing upon said spreader for maintaining said prong in a predetermined normal position with respect to said body and for maintaining said spreader against longitudinal movement with respect to said body in the direction of said prong, said leg portions when moved beyond said spreader upon movement of said prong relative to said body against said spring means being operated towards each other to permit ready insertion of said legs and shoulders into the perforation of the sheets to be clamped, and said legs on being released moving under the action of said spring means to their normal position with respect to said body and spreader at which said legs are in spaced parallel position, whereby to clamp said sheets between said body and said shoulders.

3. In a device for clamping perforated sheets in superposed relation, a body having an opening, a substantially U-shaped clamping prong slidable through said opening and having its outer leg portions provided with shoulders and normally biased towards each other under their own spring tension, a spreader resting against said body and positioned between said legs for maintaining said leg portions in normally spaced relation and forming therewith a cross-sectional area of a diameter equal to the diameter of the perforations of the sheets to be clamped, said leg portions forming when in substantial engagement a combined uniform cross-section for a distance at least equal to the total thickness of the sheets to be

clamped, said spreader and said body taken in the longitudinal direction of said prong, a coiled tension spring surrounding said prong, said spring having one end engaging the inner end of said prong and having its other end engaging said spreader for maintaining said prong in a predetermined normal position with respect to said body and for maintaining said spreader against longitudinal movement with respect to said body in the direction of said prong, said legs when moved beyond said spreader upon movement of said prong relative to said body against said spring being operated towards each other to permit ready insertion of said legs and shoulders into the perforations of the sheets to be clamped, and said legs on being released moving under the action of said spring to their normal position with respect to said body and spreader at which said legs are in spaced parallel position, whereby to clamp said sheets between said shoulders and said body.

4. In a device for clamping perforated sheets in superposed relation, a body having an opening, a substantially U-shaped retainer slidable through said opening and having a pair of resilient legs provided with shoulders at their outer ends and biased toward each other under their own spring tension, a spreader resting against the inside of said body and having a portion projecting through said opening and positioned between the outer portions of said legs for maintaining said legs in normally spaced relation and forming therewith a cross-sectional area of a diameter equal to the diameter of the perforations of the sheets to be clamped, said outer leg portions forming when in substantial engagement a combined uniform cross-section for a distance at least equal to the total thickness of the sheets to be clamped, said spreader and said body taken in the longitudinal direction of said retainer, spring means interposed between the inner end of said retainer and said spreader to urge said retainer into a predetermined normal position with respect to said body and to maintain said spreader against longitudinal movement with respect to said body in the direction of said legs, said legs, when moved upon movement of said retainer relative to said body against said spring means beyond said spreader, being operated toward each other to reduce their combined diameter to permit ready insertion of said legs and shoulders into the perforations of the sheets to be clamped, said legs on being released moving under the action of said spring means to their normal position with respect to said body and spreader, whereby to clamp said sheets between said shoulders and the outside of said body, a cap encasing the inner end of said retainer and adapted to receive said spring means, and locking means for locking said retainer and cap comprising a pin passed through said cap and between the bend of said legs.

5. In a device for clamping perforated sheets in superposed relation, a body having an opening, a substantially U-shaped retainer slidable through said opening and having a pair of resilient legs provided with shoulders at their outer ends and biased to engage each other under their own spring tension, a spreader resting against said body and having a portion projecting through said opening and positioned between said legs for maintaining the outer portions of said legs in normally spaced relation and forming therewith a cross-sectional area of a diameter equal to the diameter of the perforations of

the sheets to be clamped, said outer leg portions forming when in engagement a combined substantially uniform cross-section for a distance at least equal to the total thickness of the sheets to be clamped, said spreader and said body taken in the longitudinal direction of said retainer, spring means interposed between the inner end of said retainer and said spreader for maintaining said legs in a predetermined normal position with respect to said body and for maintaining said spreader against longitudinal movement relative to said body in the direction of said legs, said legs when moved beyond said spreader upon movement of said retainer relative to said body against said spring means engaging each other to permit ready insertion of said legs and shoulders into the perforations of the sheets to be clamped, said legs moving on being released by said spring means under the action of said spring means to their normal position with respect to said body and spreader at which said legs are in spaced parallel position, whereby to clamp said sheets between said shoulders and said body, a cap encasing the inner bent portion of said retainer and adapted to receive said spring means, and a locking member for securing said cap to said retainer comprising a pin passed through said cap and between the inner surface of the bend of said legs, and a circumferential slit wire engaging a groove in said cap for locking said pin.

6. A clamping device comprising a body having an opening, a retainer slideable through said opening and having a pair of resilient legs biased towards each other under their own spring tension and having their outer ends provided with shoulders, a spreader in fixed relation to said body and positioned between said legs for maintaining the outer portions of said legs in normally spaced relation and forming therewith a cross-sectional area of a diameter equal to the diameter of the perforations of the sheets to be clamped, the outer portions of said legs sliding through said opening and being off-set towards each other to form when in engagement due to their inherent resiliency a combined uniform cross-section for a distance of the order at least equal to the total thickness of the sheets to be clamped, said spreader and said body taken in the longitudinal direction of said retainer, spring means interposed between the inner end of said retainer and said body for urging said retainer into a normal retracted position with respect to said body, said legs when moved beyond said spreader upon movement of said retainer relative to said body against the action of said spring means being operated toward each other to permit of ready insertion of said legs and shoulders into the perforations of the work to be clamped, and said legs on being released moving under the action of said spring means to their normal position with respect to said body at which said legs are at a spaced parallel position, whereby to clamp said work between said shoulders and said body.

7. In a clamp for clamping sheets through perforations therethrough, a body member having an opening, a clamping element projecting through said opening and constituted by a unitary wire member bent in U-fashion to provide a pair of resilient prongs, said prongs having a first pair of parallel sections adjacent to the bend thereof, a pair of inwardly bent intermediate sections and a pair of outer parallel sections having shoulders and biased towards each other, a

spreader in fixed relation to said body and interposed between said prongs, and means including spring means interposed between said body and said element for causing clamping action between said body and said shoulders upon movement of said element towards said body by compression and subsequent release of said spring means.

8. In a clamp for clamping sheets through perforations therethrough, a body member having an opening, a clamping element projecting through said opening and constituted by a unitary wire member bent in U-fashion to provide a pair of resilient prongs, said prongs having a pair of parallel sections adjacent to the bend thereof, a pair of inwardly bent intermediate sections, and a pair of outer parallel sections having shoulders and biased towards each other, a spreader in fixed relation to said body and interposed between said prongs, a cap secured to the bent end of said prongs, and spring means interposed between said body and said cap for causing clamping action between said body and said shoulders.

9. In a clamp for clamping sheets through perforations therethrough, a body member having an opening, a clamping element projecting through said opening being constituted by a unitary wire member bent in U-fashion to provide a pair of resilient prongs, said prongs having a first pair of parallel sections adjacent to the bend thereof, a pair of inwardly bent intermediate sections, and a pair of parallel outer sections having shoulders and biased towards each other, a spreader in fixed relation to said body and interposed between said prongs, a cap, a removable cross pin passed through diametrical perforations in said cap and embraced by the bent end portion of said prongs, means for locking said pin in position and spring means interposed between said body and said cap for causing clamping action between said body and said shoulders.

10. In a clamp for clamping sheets through perforations therethrough, a body member having an opening, a clamping element projecting through said opening and constituted by a unitary wire member bent in U-fashion to provide a pair of resilient prongs, said prongs having a first pair of parallel sections adjacent to the bend thereof, a pair of inwardly bent intermediate sections, and a pair of outer parallel sections having shoulders and biased towards each other, a spreader in fixed relation to said body and interposed between said prongs, a cap having a circumferential groove, a removable cross pin inserted in diametrical perforations of said cap and embraced by the bent end portion of said prongs, a slit ring in said groove for locking said pin and spring means interposed between said body and said cap for causing clamping action between said body and said shoulders.

11. In a clamp for clamping sheets through perforations therethrough, a body member having an opening, a clamping element projecting through said opening and constituted by a unitary wire member bent in a U-fashion to provide a pair of resilient prongs having shoulders at the ends thereof and biased towards each other, a spreader in fixed relation to said body and interposed between said prongs, a cap, a removable cross pin inserted in diametrical perforations of said cap and embraced by the bent portion of said prongs, locking means for said pin, and spring means interposed between said body and said cap for causing clamping action between said shoulders and said body.

12. In a clamp for clamping sheets through perforations therethrough, a body member having an opening, a clamping element projecting through said opening and constituted by a unitary wire member bent in U-fashion to provide a pair of resilient prongs having shoulders at the ends thereof and biased towards each other, a spreader in fixed relation to said body and inter-

posed between said prongs, a cap having a circumferential groove, a removable cross pin inserted in diametrical perforations of said cap, a slit ring in said groove for locking said pin, and a spring means interposed between said body and said cap for causing clamping action between said shoulders and said body.

PETER F. ROSSMANN.
